UNITED STATES PATENT OFFICE.

HARVEY A. STEVENS, OF BUFFALO, NEW YORK.

ANNUNCIATOR.

1,207,655.

Specification of Letters Patent.

Patented Dec. 5, 1916.

Application filed January 3, 1916. Serial No. 69,900.

To all whom it may concern:

Be it known that I, HARVEY A. STEVENS, a citizen of the United States, residing at Buffalo, in the county of Erie and State of New York, have invented new and useful Improvements in Annunciators, of which the following is a specification.

My invention pertains to annunciators; and it contemplates the provision of a simple and inexpensively installed annunciator, constructed with a view to making known to a person in authority when gasolene or other liquid in a tank is dangerously low.

The annunciator is also, by preference, constructed with a view to enabling the person in authority to ascertain, whenever necessary, the amount of gasolene or other liquid in the tank.

With the foregoing in mind the invention in all of its details will be fully understood from the following description and claim when the same are read in connection with the drawings, accompanying and forming part of this specification, in which:

Figure 1 is a view showing in diametrical section a tank equipped with my improvement and also showing diagrammatically a normally-open electrical circuit in which my improvement is arranged. Fig. 2 is a detail plan of a portion of the tank top.

Similar numerals of reference designate corresponding parts in both views of the drawings.

In the present and preferred embodiment of my invention the tank 1 is provided in its top with a threaded aperture 2 which may be used if desired, as the filling aperture, and which is normally closed by a threaded and removable plug 3. The said plug is chambered, as indicated by 4, and flanged as indicated by 5, and to the said flange of the plug is attached by screws 6 a plate 7 in which is a central aperture 8 and one or more vent apertures 9; the latter being provided in order to permit fumes to escape from the tank and in that way lessen the liability of an explosion. It will also be observed that from the bottom of the plug chamber a guide tube 10 depends; said guide tube being connected with the plug in any manner compatible with the purpose of my invention. Pivoted at 11 on the plate 7 is a closure plate 12, having a finger-piece 13 whereby when desired the closure plate can be swung from over the aperture 8.

Movable in the tank is a float 14, the stem 15 of which is carried upwardly through the tube 10 and into the chamber of the plug and terminates at its upper end in a contact button 16.

Arranged in and electrically isolated from the plug 3 is a terminal plate 17, designed and adapted to coöperate with the button 16 in closing a normally-open electrical circuit and actuating a signal when the supply of gasolene in the tank is almost exhausted. Any suitable circuit arrangement may be resorted to, such, for instance, as the one illustrated in which a conductor 18 leads from the plate 17 to the plus pole of a source of electric energy 19, the negative pole of which is connected through a conductor 20 with an audible or visible signal 21 which, in turn, is connected through a conductor 22 with the tank 1. Thus it will be manifest that when the button 16 contacts with the plate 17, the circuit will be completed and the signal or annunciator 21 actuated to apprise the person in authority of the low stage of gasolene or fluid.

When deemed desirable, the conductor 22, instead of being connected to the tank 1, may be connected to a terminal 23 arranged on but insulated from the terminal 17 and designed to contact with the button 16 when the latter is in contact with a projection 24 on terminal plate 17.

When at any time the person in authority desires to ascertain the quantity of gasolene in the tank, it is simply necessary for such person to swing the plate 12 from over the aperture 8, whereupon the stem 15 will be raised by the float 14 through the aperture 8, and will indicate the quantity of gasolene in the tank.

My improvement is designed especially for use on motor vehicles, but is obviously designed to be used to advantage in other connections.

Having described my invention, what I claim and desire to secure by Letters-Patent, is:

The combination of a tank having an aperture in its top, a plug having a marginal flange and also having a chambered portion depending from said flange and seated in said aperture and further having an aperture in the bottom of the chambered portion, a plate secured over the chambered portion of the plug, horizontally-movable means at-

tached to the plate and normally resting over and closing said aperture, a terminal in the chamber of the plug, and a float movable in the tank and having a stem extending through the aperture in the bottom of the plug and adapted to move through the aperture in the plate when the horizontally-movable means is displaced and also having means on the stem and movable in the cham-

ber of the plug and adapted to contact with 10 said terminal.

In testimony whereof I have hereunto set my hand in presence of two subscribing witnesses.

HARVEY A. STEVENS.
